UNITED STATES PATENT OFFICE.

MALCOLM WILLIAMS, OF PASADENA, CALIFORNIA.

DESIGN FOR A PENCIL-HOLDER.

SPECIFICATION forming part of Design No. 30,830, dated May 23, 1899.

Application filed April 23, 1899. Serial No. 714,920. Term of patent 14 years.

To all whom it may concern:

Be it known that I, MALCOLM WILLIAMS, of Pasadena, in the county of Los Angeles and State of California, have invented and produced a new and original Design for a Pencil-Holder, of which the following is a full, clear, and exact specification.

Reference is to be had to the accompanying drawings, in which similar characters of reference indicate corresponding parts in both figures.

The design relates to an attachment adapted 15 to fit on the end of a pencil for holding the same in the pocket.

The design consists of the cylindric body having the outer surface studded with conical projections, as shown. 20

I claim—

The design for a pencil-holder herein shown and described.

MALCOLM WILLIAMS.
